PLUMBING FITTING HANDLE OR THE LIKE

Stephen A. Young, Monticello, Ind.
(Flora, Ind. 46929)

Filed Jan. 22, 1969, Ser. No. 15,437

Term of patent 14 years

Int. Cl. D23—01
U.S. Cl. D23—28

Fig. 1

Fig. 2

FIGURE 1 is a side elevation of a plumbing fitting handle or the like embodying my new design.

I claim:

The ornamental design for plumbing fitting handle or the like, substantially as shown.
